UNITED STATES PATENT OFFICE

116,360

DESIGN FOR A PORTABLE ELECTRIC CUTTING MACHINE OR SIMILAR ARTICLE

Frederick J. Clark, Buffalo, N. Y., assignor to
Eastman Machine Company, Buffalo, N. Y.

Application April 22, 1939, Serial No. 84,492

Term of patent 14 years

To all whom it may concern:

Be it known that I, Frederick J. Clark, a citizen of the United States, residing at Buffalo, Erie County, State of New York, have invented a new, original, and ornamental Design for a Portable Electric Cutting Machine or Similar Article, of which the following is a specification, reference being had to the accompanying drawing, forming a part thereof.

In said drawing:

Fig. 1 is a perspective view of a portable electric cutting machine showing my design.

Fig. 2 is a side elevational view of the side thereof opposite to that shown in Fig. 1.

I claim:

The ornamental design for a portable electric cutting machine or similar article, substantially as shown.

FREDERICK J. CLARK.
